(57) CLAIM

The ornamental design for a garment, as shown and described.

DESCRIPTION

FIG. 1 is a plan view of the garment showing my new design, wherein the shawl is opened and the fastening straps are extended;

FIG. 2 is a plan view from below of the garment thereof;
FIG. 3 is a front view of the garment, wherein the shawl is opened and the fastening straps are crossed;

FIG. 4 is rear view of the garment in the configuration shown in FIG. 3;

FIG. 5 is a front view of the garment, wherein the shawl is closed and the fastening straps are crossed and protruding;
FIG. 6 is a rear view of the garment in the configuration shown in FIG. 5;

FIG. 7 is a side view of the garment wherein the shawl is closed and elevated and the fastening straps are enclosed by the shawl; and,

FIG. 8 is an opposite side view of the garment in the configuration shown in FIG. 7.
